TEXTILE MACHINE

John A. Bradshaw, Greenville, S. C.

Application October 29, 1952, Serial No. 317,426

12 Claims. (Cl. 57—136)

This invention relates to improvements in a textile machine, particularly a ring twister or spinner and the like.

An object of the invention is to provide a means of adjustment which will secure the horizontal alignment of the rings, spindles, and associated elements over a wide range of spindle spacing.

Another object of the invention is to provide a means of securing the rings, spindles, and associated elements in place which will eliminate the need of accuracy in drilling location holes, bolt holes, and the like.

Another object of the invention is to provide a means of securing the rings, spindles, and associated elements in place which will permit readily changing the gauge of machine.

Another object of the invention is to provide a means of adjustment which will provide for changing the spacing between the spindle rail and the roller beam.

Another object of the invention is to provide a means of adjustment which will secure the vertical spacing between the spindle rail and ring rail.

Another object of the invention is to provide a spindle rail, ring rail, roller beam, and elements associated therewith made of extruded material, metal and composition mouldings, and rolled shapes, etc., in which elongated slots and the like may be readily provided. However, the preferred composition is presently an extruded aluminum shape.

Another object of the invention is to provide gauging aids which will be adaptable for use for changing the gauge of a machine.

With these and other objects in view, the invention consists of certain novel features of construction as will be more fully described and particularly pointed out in the appended claims.

In the accompanying drawings:

Figure 1 is a side elevational view of a fragmental portion of a textile machine embodying one form of my invention;

Figure 2 is a sectional view taken transversely through the machine shown in Figure 1 and showing various parts of the machine on either side thereof supported intermediate the ends thereof by an intermediate support or sampaon;

Figure 3 is an end elevational view of an intermediate sampaon shown in Figures 1 and 2 and with the spindle rail and roller beam shown attached thereto;

Figure 4 is a top plan view of the upper portion of the sampaon shown in Figure 3;

Figure 5 is a sectional view taken laterally through the spindle rail and showing a spindle bracket attached thereto;

Figure 6 is a top plan view of a fragmental portion of the spindle rail shown in Figure 5 and with the spindle bracket attached to it;

Figure 7 is a side elevational view of the ring rail guide rod and the manner in which the same is supported from the spindle rail and the roller beam;

2

Figure 8 is a front view of a portion of the ring rail support therefrom connecting said ring rail to the guide rod shown in Figure 7;

Figure 9 is a sectional view taken substantially along lines 9—9 of Figure 7;

Figure 10 is a sectional view on an enlarged scale of a fragmental portion of the upper side portion of the machine;

Figure 11 is a perspective view of the ring rail and an individual support for the twister ring;

Figure 12 is a perspective view of the fragmental portion of the thread board shown on an enlarged scale and the hinge block by which the same is mounted on to the machine;

Figure 13 is a sectional view through the roll beam illustrating the front roll stand support as mounted on the roller beam;

Figure 14 is a fragmental front elevational view of the front rollers and the stand for supporting the same;

Figure 15 is a top plan view illustrating the mountings for the top pressure roller of the front rollers shown in Figures 13 and 14; and

Figure 16 is a sectional view taken substantially along lines 16—16 of Figure 13 showing the manner in which the cap bars are supported on the front roller stand.

Referring to the drawings, particularly Figure 2, 20 designates generally a ring twister, the frame of which is symmetrically arranged so as to provide a machine having two similar sides 21, 21' (Figure 2) positioned back-to-back and with the spindles on one side in line with the spindles on an opposite side and other parts thereof corresponding. As the sides are similar, only one will be described with similar parts on the other side being indicated by a similar but primed number. The frame of the machine includes generally vertically extending end portions, not shown, and a number of intermediate vertical supports or adjustable samps 22 (Figure 3) which may be equally spaced lengthwise of the machine. Each sampaon (see Figure 3) is made of a horizontally extending spindle rail spreader 23 adjustably attached at the end portion thereof to vertical posts 24, 24' as at 25, 25'. These vertical posts may be of tubular stock, and at the upper end thereof there is adjustably attached in horizontal position a roller beam or upper spreader 26 as at 27, 27'. The lower end of each post 24 has a foot portion 28 which rests on the floor and is adjustably secured on the post by having a threaded relation therewith, the same being locked in adjusted position by means of a lock nut 29. Thus, the sampaon may be adjusted for any variation in floor level.

The spindle rail or lower spreader 23 is provided at each end thereof with a mounting pad 30, 30' having slotted openings 31 extending inwardly from one edge thereof. These pads provide for attaching to the sampaon, the spindle rail 32 which extends horizontally between the said end supports. The spindle rail 32 is preferably made of aluminum material extruded in a form so as to provide a recess 33, a lip portion 34, a T slot 35 at the upper front edge of the rail, and a T slot 36 at the lower edge of the rail. The pad 30 is received in said recess and the lip 34 rests upon the upper edge of the spreader 23. Bolt fastenings 37 extend through suitable openings in the said spindle rail and project through the opening 31 to be engaged by jam nuts 38 so as to secure the spindle rail to said spreader 23. Thus the spindle rail 32 is mounted to said spindle rail spreader 23 to be adjustably moved within the spreader along said post 24.

The roller beam spreader 26 is provided with mounting pads 40, 40', each having an upstanding lip 41, 41' and a plurality of slotted openings 42, 42' extending inwardly from an edge thereof (see Figure 4). A roller beam

43 preferably made of aluminum material is extruded in the form shown in cross section so as to provide right angularly extending sides 44, 45 and with the lower portion of the side 45 enlarged to provide a T-shape slot 46 extending lengthwise of said beam. The roller beam 43 is also secured at its ends to the said end frame, not shown, and intermediate the ends thereof to said sampsions. The upper side 44 engages against the pad 40 in abutting relation with the lip 41 (Figure 10). Bolts 47 extend through the side 44 and through the 10 openings 42 to receive a jam nut 48 to securely clamp the said roller beams to the pad 40. Thus the beam 43 is attached to the spreader 26 to be adjustably moved with the spreader on the posts 24, 24'.

The spindles indicated generally 51 (Figure 1) are mounted on the spindle rail 32 by means of individual brackets 52 (see Figures 5 and 6) having a central opening 53 extending therethrough and through which the bolster housing 54 (see Figure 2) of the spindle projects to be threadedly engaged by a jam nut 55. The bracket 20 52 engages against the upper front portion of the spindle rail 32 and has spaced projections 56 which slidably extend into the entrance opening of the T slot 35 so as to be properly located in position. Bolts 57 extend through suitable openings 58 in the bracket and project therefrom to engage nuts 59a slidably received in the head of the 25 T slot 35 to secure the bracket 52 in adjusted position on the said spindle rail 32. Thus the spacing of the spindles 51 may be readily adjusted lengthwise of the frame by merely loosening the bolts 57 and sliding the bracket 52 along the rail 32 to the desired location and thereafter retightening the said bolts 57.

The ring rail 59 (see Figures 7, 11) is also preferably made of aluminum material extruded in a form generally L shaped in cross section providing a leg portion 60 and an arm portion 61 projecting therefrom at an acute angle to the leg 60. The end of the arm portion 61 has a T slot 62 therein extending lengthwise thereof. In mounting the ring rail on the machine, the same is placed in the position shown with the arm portion 61 projecting toward the spindle at a location inwardly thereof, which positions the T slot 62 to open on the underside of the said arm portion 61 thereby protecting the slot from falling lint and the like lodging therein. The twister rings 63 (see Figure 11) are of a usual construction and each is supported in an individual holder 64 having a flange 65 provided with spaced openings 66 therethrough. The flange 65 is positioned to engage the underside of the ring rail 59 as best seen in Figure 7, and bolts 67 having a head slidably received in said T slot 62 project therefrom and through said openings 66 to be threadedly engaged by jam nuts 68 to secure the said holder 65 in adjusted position along said ring rail whereby said ring 63 may be properly positioned in line with selected spindle 51.

The so-called thread board 70 (see Figures 10, 12) to which the thread guides 71 are attached is also made preferably of extruded aluminum material and has a T slot 72 opening on the underside thereof. The thread board 70 is hingedly secured to the roller beam 43 as by means of hinge blocks 73, best seen in perspective in Figure 12, which blocks are also made of extruded material of extended lengths and then severed to a desired length. Each block, of which there may be as many as is found necessary, has a T slot 74 opening on one side thereof and a ledge or stop abutment 75 on an opposite side. Each block 73 is secured to the roller beam 43 by means of a bolt fastening 76 (Figure 10) having a head thereon received in the said T slot 74 and with the shank thereof projecting through a suitable opening in the roller beam 43 and engaged by a jam nut 77 which secures the said block in place. The thread board 70 has a notch 78 cut therein to receive the block 73, the abutment 75 extending inwardly of said notch and beneath the thread board so as to provide a rest or abutment for said thread 75

board to engage when in the horizontal operative position thereof. A hinge pin 79 extends through the thread board and the said blocks 73 whereby said thread board may be swung to a vertical inoperative or horizontal operative position as the conditions may require. The 5 thread guides 71 are of a usual type having a thread guiding end portion 80 and pivotally mounted on individual brackets 81 as at 82. Each bracket 81 is secured to the underside of the thread board 70, as best seen in Figure 10, by means of a fastening screw 83 which engages a nut 84 slidably received in the said T slot 72. Thus each thread guide is individually mounted in adjusted position lengthwise of said thread board and may be individually swung to an inoperative position as indicated in dotted lines 85 or the thread board as previously stated may be swung upwardly as indicated in dot and dash lines 86 to place all of the said thread guides 71 thereon out of operative position.

The front rolls indicated generally 90 (Figures 2 and 13) are supported in a manner to provide adjustability thereof lengthwise of the machine and comprise a lower roller 91 which is supported in roller stands 92 (see Figures 1, 2, and 13), there being as many of the stands 92 as will be found necessary for the particular length of the machine. The stands 92 may also be made of aluminum material extruded in extended lengths to be thereafter severed into proper lengths for use. Each stand has a foot portion 93 (Figure 13) provided with a T slot 94 and a depending lip 95. The foot portion 93 engages the upper side 44 of the roller beam 43 (see Figure 13) and the lip 95 engages the side 45, which provides for aligning the stand in proper place on the said roller beam 43. A tie bolt 96, the head of which is slidably received in the T slot 94, projects therefrom through suitable openings in the side 44 to be engaged by a jam nut 97 to firmly secure the stand 92 in place. The upper portion of the stand has spaced recesses 98, 99 extending inwardly from the upper edge of the stand. These openings are of rectangular form, and the opening 98 provides a bearing in which is journaled the said roller 91. The usual half-bearing block 100 may be positioned between the bottom of the recess 98 and the bearing portion 101 of the roller 91.

A cap bar 102 (see Figures 15 and 16) extends between pairs of adjoining stands 92 and has its end portions reduced as at 103 to provide a shoulder 104 at either end thereof. The reduced portions 103 are received in the recess 99 of adjacent stands and there secured in place as by means of screw fastenings 105, the said shoulder 104 preventing movement longitudinally of the said cap bars 102. The cap bars 102 provide supports on which are mounted a plurality of pairs of spaced brackets 106, each having a foot portion 107 provided with an opening therethrough of a size and rectangular shape corresponding to the cross sectional shape of the bar 102 to be slidably received thereon and adjustably secured thereto as by means of a fastening 108. The brackets 106 extend upwardly from the cap bar 102, and the upper end portion thereof is provided with recesses 109, the walls of which extend in a generally vertical direction. A pressure roller 110, one for each spindle 51, is supported by pairs of said brackets 106 and is provided with trunnions 111 (Figure 15) which are received in said recesses 109 to be guided thereby toward and from the bottom roller 91 in a usual manner common to drawing rollers of machines of this character.

The machine is also provided with the separators 112 (Figures 1 and 2) which are positioned substantially midway between adjacent spindles 51 (see Figure 1). Each separator 112 is hung from a bracket 113 (see Figure 10) having an upstanding flange 114 provided with an opening 115. The bracket engages the lower edge of the beam 43 and the flange 114 engages the rear of the side 45 of the beam. A bolt 116, the head 117 of which is slidably received in the T slot 46 and the shank of the bolt

extends therefrom to be received in said opening 115 to project therethrough and is engaged by a jam nut 118 to adjustably secure said bracket 113 in place.

Each separator has a vertical row of holes 112", any one of which can be engaged on the raised button 113" of the bracket 113 to secure the most favorable disposition of the separator 112. It is only necessary to spring or bow the separator inwardly at the location of the button 113" to release it from the bracket and then the separator may be sprung back into place to be secured on the cast button 113" by means of any one of the vertical holes. This adjustment is especially desirable when the vertical spacing between the roller beam and the spindle rail is to be varied as when changing to another bobbin traverse.

As is usual in machines of this character, the spindles 51 thereof are driven from a drive drum 119 (Figure 2) which has a shaft 120 rotated by a drive mechanism, not shown, and usually housed at the end of the machine, not shown. In the present instance the shaft 120 extends lengthwise of the machine and is supported intermediate its ends by means of a bracket 121 which is slotted at 122 for adjustably positioning on the roller beam spreader 26 substantially midway thereof to depend therefrom and is secured thereto. The shaft 120 is journaled in the bracket 121 and is thus fixed relative to said roller beam spreader 26. Motion is transmitted from the drum 119 to the spindles on each side of the machine by means of an endless tape or belt 123 which is guided and tensioned by means of idler rollers 124, 124' journaled for free rotation in brackets 125, 125'. These brackets are pivotally mounted on rods 126, 126' which extend lengthwise of the machine and are supported intermediate the ends thereof on the spindle rail spreaders 23 of the machine. The arm 125 and opposite arm 125' are resiliently biased toward each other by means of a pull spring 126, the ends of which are secured in an appropriate manner to the said arms 125, 125'. It will be, of course, understood that there is a pair of these rollers 124, 124' for each belt and that each belt is arranged to drive two adjoining spindles 51 on each side of the machine.

Although the roller beam spreader 26 is adjustable on the rods 24, 24', it is intended that this adjustment be only used for the initial positioning of the spreader, as the vertical position of this spreader must be such that the front rolls 90, 90' line up exactly with the gear drives in the geared end of the frame. The slots 122 and the brackets 121 are used to permit the shaft 120 to be adjusted relative to the front rolls and so as to align the shaft perfectly with the motor drive at the end of the frame and the gearing at the geared end of the frame. Once this proper spreader position is established it is not likely that it would again be changed unless the entire machine is to be raised or lowered by adjusting all of the adjustable feet at the geared and foot ends and samps.

An important feature of this machine lies in its capacity to suit any reasonable change in bobbin traverse through the raising or lowering of the spindle rail spreader 23 and spindle rail 32 relative to the roller beam spreader 26 and the roller beam in the above-mentioned fixed position. In changing the machine from a given traverse to a longer traverse, for example, it is possible to lower the spindle rail spreader 23 at each samps an appropriate amount to establish the spindle rails in a lower position. This lower position is necessary to accommodate the longer bobbins on the same spindles with suitable ballooning space between the upper head of the bobbin and the thread guides 71 and 71'. This same lowering requires that the rods 126 and 126' and also the idlers 124 and 124' be lowered by the same amount, since the rods 126 are fixed to the spreader 123 and thus there will be preserved the same tape drive line horizontal to the spindles. The arms 125 and 125' 75

will swing outwardly slightly to compensate for the needed extension in perimeter of the tape 123 and the pull spring 126 will maintain tension in this new idler position. The builder cross shaft 149, pivoted brackets 148, 148', and all other parts that are suspended from the spindle rail would still operate properly in their lowered position, and it is a simple matter to re-establish the drive to the builder in the geared end to suit the lower position.

10 In the present embodiment of the invention the ring rail 59 is fastened to a bracket 127 (see Figures 2, 7, and 8) as by means of bolt fastenings 128 extending through said bracket and the side 60 of the ring rail. The bracket 127 is guided in its movement by means of a guide rod 130, the upper end of which is secured by means of a bracket 131 having an opening 132 in which the upper end portion of the rod is received and therein secured by means of a fastening screw 133. The bracket 131 engages against the lower edge of the roller beam 43 (see Figure 13) at the rear thereof and is provided with spaced lip portions 134 which extend to engage the lower edge of the said beam 43 and is secured as by means of fastening 135 which are slidably related in the T slot 46. The guide rod 130 is additionally supported at a lower part thereof by means of a bracket 136 (see Figure 7) which is provided with an opening 137 through which the rod 130 passes and is secured to the bracket by means of a fastening 138. The bracket has a flange portion 139 (see Figure 9) which extends beneath the spindle rail 32 to engage therewith, and a T bolt 140 engages in the T slot 36 to project therefrom and through said flange 139 to be engaged by a jam nut 141 to secure the said bracket 136 in place. The bracket 127 is provided with a rigid extension 142 which is bolted to the bracket as by means of fastenings 143. This extension 142 is provided with a longitudinal opening 142a therethrough and through which the neck portion 144 of the bracket 136 projects. The lower portion of the extension is provided with a foot 145 through which an opening 146 extends for passage of the rod 130 therethrough.

It will now be apparent that raising or lowering said extension 142 will in turn raise or lower the bracket 127 along the guide rod 130 and thereby traverse the ring rail 59.

45 The motion for traversing the ring rail 59 is provided by a usual builder motion, not shown, through which a rod 147 (Figures 1 and 2) is reciprocated axially lengthwise of the machine in a usual manner. There is secured to the lower portion of the spindle rail 32 a plurality of brackets 148, one only on each side being shown but it being understood that a number of these are provided depending upon the length of the machine and in numbers corresponding to the number of lifter brackets 127. There is journaled in the brackets 148 a shaft 149 on which is mounted a lever 150 extending generally upwardly therefrom into engagement with a block 151 secured to the said rod 147. There is also secured on the shaft 149 (see Figure 1) a lever 152 having at the free end thereof a roller 153 which extends into engagement with the foot portion 145 of the extension 142. Thus, as the rod 147 is moved toward the left as seen in Figure 1, the shaft 149 will be rocked counter-clockwise, thereby rocking the lever 152 to swing the roller 153 in an upward direction and thereby raise the ring rail 59 upwardly. The return of the ring 59 to the lower position thereof is effected in a usual manner by gravity.

60 It is also contemplated that the supply package or creel supporting structure may be so arranged that the supply package spindle 159 may be adjustable lengthwise of the machine in accordance with the position of the spindles. To this end a laterally extending bar 160 is fastened in an appropriate manner, not shown, to the 65 roller beams 43 and is provided substantially midway

thereof with an apertured boss 161 in which is received a standard 162 secured in place by means of a fastening 163 which may be a usual bolt. This standard 162 supports a bracket 164 having two similar sides 165 and 165' on which is secured a creel rail 166. This rail 166 5 preferably is made of aluminum material extruded in a form so as to provide a T slot 167 extending lengthwise thereof. The inner ends of the creel pins 159 are reduced as at 169 providing shoulders to receive thrust washers, and then threaded so as to engage into nuts 168 slidably received in the T slot 167. The creel pin is further provided with an opening 170 to receive the pin or like tool to turn the said creel pin into the nut 168.

It will now be apparent that I have disclosed a textile machine in which the several rails may be advantageously made of extruded material with a slot to provide simple, inexpensive anchorages for tie bolts employed for securing the associated elements of the machine in place. Slots formed by this extrusion do not require breaking of the skin of the extruded material such as by machining, which is known to weaken the extrusion and sometimes permit of warpage of the rail. It will also be apparent that the rails made as above described provide a choice of spindle spacing which may be readily changed without additional machining of parts and which rails provide an efficient means for securing horizontal alignment of spindles and associated elements. The invention also contemplates the use of the several parts as aids in regauging an existing machine of the above type. The term "member extending lengthwise of the machine" is 20 herein employed to designate the horizontal beams or bars some of which are usually referred to specifically as "creel rail," "spindle rail," "ring rail," "thread board," and "roller beam."

I claim:

1. In a textile machine having a spindle rail for supporting a plurality of spindles, a ring rail for supporting a plurality of rings, a thread board for supporting a plurality of thread guides, and a roller beam for supporting the front rollers of the machine, and means for adjustably securing rings, thread guides and front rollers to their respective rails in vertical alignment with each other and said spindles at any different spacing of said spindles, said ring rail having a T slot extending lengthwise thereof, individual supports for said rings, and fastening means engaging individual supports and the walls of said T slot for adjustably securing said supports to said ring rail.

2. In a textile machine having a ring rail, a roller beam rail, and a thread board rail, means for adjustably securing rings, front rollers, and thread guides to their respective rails in vertical alignment with each other and at different spacings along said rails, a spindle rail having a slot with overhanging edges extending lengthwise thereof, individual supports for each of a plurality of spindles, and fastening means engaging said individual supports and the walls of said slot for adjustably securing said supports to said spindle rail.

3. In a textile machine having a spindle, a roller beam rail, and a thread board rail, means for adjustably securing spindles, front rollers, and thread guides to their respective rails in vertical alignment with each other and at different spacings of said spindles, a ring rail having a slot with overhanging edges extending lengthwise thereof, individual supports for each of a plurality of rings, and fastening means engaging said individual supports and the walls of said slot for adjustably securing said supports to said ring rail.

4. In a textile machine having a spindle rail, a ring rail, a roller beam rail, means for adjustably securing spindles, rings, and front rollers to their respective rails in vertical alignment with each other at any different spacing along said rails, a thread board rail having a slot with overhanging edges extending lengthwise thereof,

5. individual supports for each of a plurality of thread guides, and fastening means engaging said individual supports and the walls of said slot for adjustably securing said supports to said thread board rail.

5. In a textile machine having a spindle rail, a ring rail, a thread board rail, means for adjustably securing spindles, rings, and thread guides to their respective rails in vertical alignment with each other and at different spacings of said spindles, a roller beam rail having a slot with overhanging edges extending lengthwise thereof, individual supports for each of a plurality of front rollers, and fastening means engaging said individual supports and the walls of said slot for adjustably securing said supports to said roller beam rail.

6. In a spinning or twisting machine, a frame comprising samps, at least one of which has spaced vertical posts, an upper spreader, means to secure said upper spreader to said posts, a lower spreader, means to adjustably secure said lower spreader to said posts for vertical adjustment therealong, spindles and driving means therefor carried by said lower spreader whereby adjustment of said lower spreader may vary the traverse of the work relative to the spindle.

7. In a spinning or twisting machine, a frame comprising samps, at least one of which has spaced vertical posts, an upper spreader, means to adjustably secure said upper spreader to said posts for vertical adjustment therealong, a lower spreader, means to adjustably secure said lower spreader to said posts for vertical adjustment therealong, spindles and driving means therefor carried by said lower spreader whereby adjustment of said lower spreader may vary the traverse of the work relative to the spindle.

8. In a spinning or twisting machine as in claim 7 wherein there are a plurality of samps with adjustable upper and lower spreaders, a driving drum and a shaft therefor is carried by said upper adjustable spreaders of said samps.

9. In a spinning or twisting machine as in claim 7 wherein there are a plurality of samps with adjustable upper and lower spreaders, a driving drum and a shaft therefor is carried by said upper adjustable spreaders of said samps and said lower spreaders carry the complete drive for the spindles including idlers and tapes extending about said drum and spindles.

10. In a spinning or twisting machine as in claim 7 wherein there are a plurality of samps with adjustable upper and lower spreaders, a driving drum and a shaft therefor is carried by said upper adjustable spreaders of said samps and said lower spreaders carry the complete drive for the spindles including idlers and tapes extending about said drum and spindles and also the traverse mechanism for the traversing of the work along the spindles.

11. In a textile machine having a spindle rail, a ring rail, a thread board rail, means for adjustably securing spindles, rings, and thread guides to their respective rails in vertical alignment with each other and at different spacings of said spindles, a creel rail having a slot with overhanging edges extending lengthwise thereof, individual supports for each of a plurality of creel pins, and fastening means engaging said individual supports and the walls of said slot for adjustably securing said supports to said creel rail.

12. In a spinning or twisting machine having a plurality of members extending lengthwise of the machine comprising a creel rail, a spindle rail, ring rail, thread board, and roller beam, that improvement comprising at least one of the plurality of said members being of extruded material shaped by such extrusion to have a slot with overhanging edges extending lengthwise thereof without machining through the skin of the material, thereby reducing warpage of the member, elements of the machine carried by the slotted member, fastening means having a

part in said slot for movement therealong to adjustably secure the elements along said member.
